**COMBINATION BOAT AND CANOPY FOR THE BED
OF A PICK-UP VEHICLE AND THE LIKE**

Elmer A. Ward, 3029 Aspen Drive,
Casper, Wyo. 82601

Filed July 5, 1966, Ser. No. 2,913

Term of patent 14 years

(Cl. D14—27)

FIGURE 1 is a perspective view of the combination boat and canopy for the bed of a pick-up vehicle and the like;

FIGURE 2 is a plan view thereof;

FIGURE 3 is an elevational view taken along line 3—3 of FIGURE 2;

FIGURE 4 is an end elevational view taken along line 4—4 of FIGURE 2; and

FIGURE 5 is an end elevational view taken along line 5—5 of FIGURE 2.

The broken-line showing of the pick-up vehicle or portions thereof in FIGURES 1—5 are for illustrative purposes only.

The characteristic features of my design for a combination boat and canopy for the bed of a pick-up vehicle and the like reside in the combination of the continuous narrow rim around the edge of the canopy, the configuration of the two outside runners with the sharply curved

arcuate sections at the front of the runners and the extremities of these sections extending a substantially greater distance outwardly from the bottom of the canopy than the rear section of the runners, and the rounded central runner midway between the two outside runners.

I claim:

The ornamental design for a combination boat and canopy for the bed of a pick-up vehicle and the like, as shown and described.
